UNITED STATES PATENT OFFICE.

HERBERT J. CRABBS, OF PITTSBURGH, PENNSYLVANIA, ASSIGNOR TO WESTINGHOUSE ELECTRIC & MANUFACTURING COMPANY, A CORPORATION OF PENNSYLVANIA.

SWITCH.

Application filed May 22, 1920, Serial No. 383,348. Renewed January 31, 1924.

To all whom it may concern:

Be it known that I, HERBERT J. CRABBS, a citizen of the United States, and a resident of Pittsburgh, in the county of Allegheny and State of Pennsylvania, have invented a new and useful Improvement in Switches, of which the following is a specification.

My invention relates to switches and particularly to single or double-throw-knife-blade switches such as are commonly employed on structures for connecting terminals of high-tension circuits.

Switches of this type are usually devoid of operating handles and are provided with eyelets or various forms of latches adapted to be engaged by a "hook-stick" or operating rod for moving the switch blade in and out of contact with the jaws. In service, such switches are infrequently operated and remain in closed position for long periods of time, during which interval, due to oxidation and corrosion of the contacting members, the blades becomes fastened within the jaws with such security that it becomes necessary to pry them therefrom by suitable instruments, it being frequently impossible to dislodge them quickly by using the "hook-stick" in the usual manner. In cases of emergency, serious damage may result to machinery, or the life of an operator may be endangered, by reason of the sticking of the blade within the switch jaws when it is necessary to quickly open the circuit.

One object of this invention is to provide a switch wherein the use of a "hook-stick" in the usual manner causes the blade first to be positively pried loose from the jaws by the operating lever, after which operation the blade may be entirely withdrawn from the jaws with little effort.

Another object is to provide a switch having the above characteristics wherein the latch mechanism employed is of simple, compact and inexpensive construction and wherein vital elements are protected from contact with foreign objects.

Another object is to provide a double-throw switch wherein separate latching levers engage separate latches and wherein the latch levers are counterparts and, therefore, interchangeable.

A further object is to provide a switch latching mechanism employing a minimum number of moving parts, the action of which

is positive under severe outdoor conditions.

A further object is to provide a switch latch designed primarily for double-throw switches, which is inexpensive and may be used for single-throw switches without necessitating any change in design.

These and other objects are attained by means of switch apparatus embodying the features herein described and illustrated in the drawings accompanying and forming a part hereof, wherein:

Fig. 1 is a side elevation of the improved switch apparatus, showing the blade in two operative positions.

Fig. 2 is a plan view of the operating levers showing them in assembled relation.

Fig. 3 is a side elevation of one of the operating levers showing the inner side thereof, with the position of the co-operating lever indicated in dot-and-dash lines.

Referring to the drawing, the switch includes pivot jaw member 5 and two pairs of contact jaws 6 and 7, all of which are supported upon insulated bases or pedestals 8 which are preferably secured to a switch base 9. The pivot clip 5 is provided with a terminal 10 which, for the purpose of illustration, may be considered as connected to a bus-bar receiving current from a generator (not shown). The contact jaws 6 and 7 are provided with terminals 11 and 12, respectively, which, it will be assumed, are connected to leads of two separate service circuits. The service circuits are adapted to be separately connected to the bus-bar by means of a knife-switch blade 13 which is pivoted to the pivot jaw 5 and is adapted to be swung into operative engagement with the contact jaws 6, as shown in full lines in Fig. 1, or into operative engagement with the contact jaws 7, as indicated in dot-and-dash lines in Fig. 1. The jaws 6 and 7 are of the split or jaw type well known in the art in which a pair of contact strips are held in spaced relation and so aligned with the blade as to receive the blade in the space between them and snugly contact therewith. Switches of this type are well known in the art and it is also a matter of common experience that the blades thereof become so corroded at the points of contact as to cause the blades to stick within the jaws and resist the efforts of the operator to open the switch with a "hook-stick" operated in the usual manner.

110

In order to obviate this difficulty and to apply a positive leverage to the blade sufficient to loosen it from fixed contact with the jaws, I provide the free end of the blade 5 13 with a pair of operating levers 14 and 15 which are pivoted on opposite sides of the blade by means of studs 16 and 17, respectively.

The levers 14 and 15 are counterparts 10 and, therefore, interchangeable, the former being pivoted, as shown in Fig. 1, on the far side of the blade and the latter upon the near side thereof.

Referring to Figs. 2 and 3, each lever includes a side portion 18 having a marginal flange 19 extending entirely around the periphery thereof and having a section 20 of greater depth than the flange 19 adapted to extend over the end of the switch blade 20 which lies in the space 21 between the flanges 19. The flange portion 20 is provided with a re-entrant lip or stop 22, which lies adjacent the end 23 (Fig. 1 of the drawing) and is adapted to engage the 25 blade to limit the movement of the lever with respect thereto when the lever is moved to unlatched position during the opening operation of the blade.

The lever is also provided with an 30 inwardly extending lug 24 which engages the end 23 of the blade 13 during the movement of the lever in the direction tending to move it into latching position with a stationary latch member to be hereinafter described.

The lever is provided with a pivot hole 35 25' through which the pivot studs are inserted in assembling the lever upon the blade, and the flange 19 is provided with a latch 40 recess 25 having a latch-engaging face or tooth 26 so positioned with respect to the pivot stud that, when the hook 27 is engaged by the "hook-stick" and the lever 14 is rotated in a clockwise direction, the 45 tooth rotates similarly in a direction away from the end of the switch blade.

Referring to Fig. 1, each of the jaws 6 and 7 is provided with stationary latch members 28 and 29 which, as shown, are 50 riveted to the jaw base. These latches may be made as integral parts of the jaws and, for the purpose of the claims of this specification, may be considered as parts thereof or as separate stationary latch members. 55 The latch members 28 and 29 are so disposed that they lie in planes on opposite sides of the blade and engage the levers 14 and 15, respectively, when the blade is moved into the jaws 6 and 7, respectively. 60 Each latch member is provided with a recess 30 adapted to receive the tooth 26 of its respective operating lever so that the said tooth interlocks with a similar tooth 31 on the latch member.

65 The notched side of the latch member is

so rounded at 32, adjacent the free end thereof, that it will move over a similarly rounded edge 33 on the co-operating latch member in such manner that the latch lever will be so retracted as to clear the latch member when the blade 13 is moved into operative relation with the contact jaws. 70

The latch or operating levers 14 and 15 are normally held in the position indicated in Fig. 1 by means of a helical spring 34, 75 one end of which is attached to the flange 20 of one lever, while the other end is attached to a similar flange on the other member. The spring lies within the space between the levers and is protected against contact with external or foreign objects by the housing formed by the operating levers. The spring constantly exerts a force tending to draw the lever hooks toward one another and their range of movement, in the direction in which the spring tends to draw them, is limited by means of lugs 24 which engage the end 23 of the blade 13. 80

It will be seen from the foregoing that, if a "hook-stick" were inserted in the hook 27 of the lever 14 and drawn outwardly in a direction tending to withdraw the blade from the jaws 6, the lever 14 would pivot upon the stud 16 and so move with relation to the blade as to disengage the teeth 31 and 26 of the latch member and lever, respectively. The movement of the lever 14, with respect to the blade, is limited, however, by contact of the stop 22 with the end 23 of the blade and, when the stop 22 engages 95 the end of the blade, the pull of the "hook-stick" is transmitted directly to the blade. As the latch lever is withdrawn at the time from the latch member, the blade is automatically released and may be withdrawn from the jaws, but, as has been previously pointed out, the blade frequently becomes so tightly fastened between the jaws that a direct pull on the lever 14 that would not injure it, would not be sufficient to start the movement of the blade. I have, therefore, 100 provided each of the levers 14 and 15 with a projection 35 adapted, when the lever is in latched position, to abut the extreme end of the latch member with which it co-operates in such manner that, when the lever is pulled in a direction tending to withdraw the blade, the projection 35 will fulcrum on the ends of its respective latch member and 105 positively pry the blade outwardly and loosen it from the jaw by force and leverage greater than could possibly be exerted by a direct pull of the "hook-stick" that would not injure the lever or latch. 110

It will be seen from the foregoing that, 125 when a blade is stuck within the jaws, the first unlocking movement of the operating levers, relative to the blade, forces the blade loose from the jaws, after which operation, the blade may be withdrawn with ease by 130

pulling on the "hook-stick" in the proper direction. The levers are normally held in a predetermined relation with respect to the blade by the spring 34 and automatically snap into latched relation with its co-operating latch member when the blade is moved into operative relation with the jaws.

While I have shown the latch member as a portion of the jaw structure, it is obvious that it may be mounted in any convenient manner and may be incorporated in the jaw strips, and that the lever could fulcrum upon any stationary member, not necessarily a part of the latch member, which might be joined to the jaws or be independent thereof, without departing from the spirit of my invention.

While I have described and illustrated but one embodiment of my invention, it will be apparent to those skilled in the art that various changes, modifications, substitutions, additions and omissions may be made in the apparatus illustrated without departing from the spirit and scope of the invention as set forth by the appended claims.

I claim as my invention:

1. A switch comprising a pivot jaw member, two pairs of spaced contact jaws, a switch blade pivoted to the pivot jaw member and adapted to separately engage the said contact jaws, a pair of latch levers pivoted to the free end of the switch blade and on opposite sides thereof, a latch member adjacent each pair of contact jaws and adapted to engage one of the said levers to move it into latching position when the blade is moved into operative relation with the jaws, and a spring connecting the latch levers and adapted to maintain them in yielding operative relation with respect to the latch members, the said levers being so formed as to provide a protecting housing for the spring.

2. In an electric switch, the combination

with a movable contact member, a stationary contact member and a latch member, of a pair of oppositely disposed operating levers for the movable contact member movably mounted thereon and adapted to co-operate with the latch member, for holding the said contact members in engagement with one another, and a spring adapted to normally maintain one of the operating levers in locked engagement with the latch member, the said operating levers being so formed as to provide a housing for the spring.

3. A double-throw switch comprising a pair of spaced stationary contact members, a movable contact member having its one end pivoted intermediately of the stationary contact members, a pair of latch members movably mounted on the movable contact member adjacent to its free end, a stationary latch member adjacent to each of the stationary contact members and adapted to engage one of the movable latch members, and a spring adapted to maintain each of the movable latch members in engagement with one of the stationary latch members, the movable latch members being so formed as to provide a housing for the spring.

4. In an electric switch, the combination with a movable contact member and a stationary contact member, of a stationary latch member, a pair of oppositely disposed movable latch members adapted to co-operate with the stationary latch member in order to maintain said contact members in operative relation, and a resilient member for maintaining the latch members in operative relation, the said movable latch members being so formed as to provide a housing for the resilient member.

In testimony whereof, I have hereunto subscribed my name this 17th day of May, 1920.

HERBERT J. CRABBS.
